UNITED STATES PATENT OFFICE.

LUDWIG MERTENS, OF CHARLOTTENBURG, GERMANY, ASSIGNOR TO
"ABBÉ" ENGINEERING COMPANY, OF NEW YORK, N. Y., A COR-
PORATION OF NEW YORK.

INTERNAL-COMBUSTION ENGINE.

No. 823,286.

Specification of Letters Patent.

Patented June 12, 1906.

Application filed April 21, 1904. Serial No. 204,167.

To all whom it may concern:

Be it known that I, LUDWIG MERTENS, a citizen of the Empire of Germany, residing in Charlottenburg, in the Empire of Germany, ⁵ have invented certain new and useful Improvements in Internal-Combustion Engines, of which the following is a specification.

This invention relates to improvements in two-cycle internal-combustion engines having one or more double-acting combustion-cylinders supplied with an explosive gas-and-air mixture from an independent feed-pump; and among the objects of the invention is the provision of an internal-combustion engine ¹⁵ in which the power-cylinder may be exhausted during the same stroke which is produced by an explosion and recharged before the return stroke, so that an explosion will take place for every stroke of the power-piston.

²⁰ A further object of the invention is the provision of a multiple-cylinder engine in which the feed-pump is so constructed and actuated as to charge each of the cylinders consecutively with a fresh supply of combustible mixture, ²⁵ the power-piston of each cylinder being actuated in both directions by explosions produced alternately at the ends of each cylinder.

With these ends in view the invention consists in the novel features and combinations ³⁰ of parts, which will be fully described herein-after and finally pointed out in the claims.

In the accompanying drawings, Figure 1 is a vertical longitudinal section of my improved two-cycle internal-combustion engine, taken on line E F, Fig. 2. Fig. 2 is a plan view of Fig. 1, a portion being shown in horizontal section. Fig. 3 is a vertical longitudinal section of a two-cycle internal-combustion engine with two double-acting cylinders, taken on line G H, Fig. 4; and Fig. 4 is a plan view of Fig. 3 with parts shown in horizontal section.

Similar numerals of reference indicate corresponding parts.

Referring to the drawings, 54 represents a double-acting combustion-cylinder which is provided with a number of outlets 75 at its middle portion. 55 is a single-acting feed-pump which is connected with the ends of ⁴⁵ the combustion-cylinder 54. Both the cylinder 54 and the feed-pump 55 are mounted on a base-plate 56 of any well-known construction. The power-piston 57 is connected with

the crank-pin of the crank-shaft 58 by means of the piston-rod 59 and the connecting-rod 60. In a similar manner the pump-piston 61 is connected with the crank-pin of the pump-crank-shaft 62 by means of a piston-rod 63, cross-head 64, and connecting-rod 65. The connecting-rod 65 is extended beyond the ⁵⁵ crank-pin of the crank-shaft 62 and provided with a counterweight 66. The cross-head 64 is preferably formed as a buffer-piston working in a dash-pot 67, having outlets near its middle portion. For lower speeds of ⁶⁰ the motor the dash-pot is dispensed with and the piston 64 formed as an ordinary cross-head moving in suitable guideways. The motor crank-shaft 58 is connected with the pump crank-shaft 62 by means of two gear-wheels 68 and 69, the ratio of which is two to one so as to enable the feed-pump to force a full charge of explosive mixture at each stroke of its piston alternately into each end of the cylinder 54 for every rotation of the crank-shaft 58. ⁷⁰

Gas is conducted through a tube 70 and the opened spring-pressed gas-inlet valve 71 to the pump-cylinder, while fresh air is admitted through a suitable spring-pressed air-inlet valve. (Not shown.) The piston 61 then forces the explosive mixture through the bent tube 72, the branch tubes 73, and one of the opened spring-pressed admission-valves 74 alternately into one or the other ⁸⁵ end of the cylinder 54. The explosive mixture is again compressed in the end of the combustion-cylinder during the remaining portion of the stroke of the power-piston 57 and ignited to drive the latter in the opposite direction, whereupon the burned gases escape through the uncovered outlets 75, the annular channel 76, and the outlet 77. The springs of the various inlet-valves are properly adjusted to render the latter automatic ⁹⁰ in their action. ⁹⁵

The horizontal combustion-engine shown in Figs. 3 and 4 only differs from the motor shown in Figs. 1 and 2 in this respect, that it comprises two double-acting combustion-cylinders and one double-acting feed-pump. The construction of the two combustion-cylinders 78 and 79, their pistons, and the parts connecting them with the two cranks ¹⁰⁰ 80 81 of the crank-shaft 82 is substantially ¹⁰⁵ the same as before. The double-acting feed-

pump is disposed above the two cylinders 78 and 79 and the piston of the same driven from the motor crank-shaft 82 by means of two gear-wheels 83 84, a pump crank-shaft 85, a crank-disk 86, having a crank-pin 87, a connecting-rod 88, and the piston-rod 89. The cross-head (not shown) is again assumed to be a piston reciprocating in the dash-pot 90, which is cast in one piece with the head 10 91 of the pump-cylinder 92. The two covers 91 93 of the latter are each provided with a spring-pressed air-inlet valve and a spring-pressed gas-inlet valve similar to those of the previously-described motor. These valves 15 are not shown, as their construction is not material, and may be of any known kind. On the right side of the pump-cylinder 92 the piston sucks in during one stroke air and gas through the respective valves and first partly 20 compresses the mixture and forces it then during the next stroke through the outlet 95, the bent tube 96, the branch tubes 97, and either of the respective admission-valves into one or the other end of the combustion-cylinder 25 79. On the left side of the pump-cylinder 92 the air and the gas are in a similar manner sucked in by the piston 94 during one stroke, the mixture being partly compressed and then forced during the next 30 stroke through the outlet 98, the bent tube 99, the branch tubes 100, and either of the respective admission-valves 101 into the cylinder alternately into one or the other end of the same. In both explosion-cylinders 78 35 and 79 the explosive mixture admitted is again compressed during the remaining part of the piston-stroke and finally ignited, whereupon the explosion throws the piston back, and at the end of the next stroke the 40 burned gases escape through the outlets 102, the annular channel 103, and the outlet 104 into the atmosphere. The ratio of the two gear-wheels 83 and 84 is two to one, so that the pump crank-shaft 85 makes two rotations 45 for every rotation of the motor crank-shaft 82. This ratio is necessary, so that the feed-pump is enabled to force a full charge of explosive mixture during one stroke into the one combustion-cylinder on either side and 50 during the other stroke into the other combustion-cylinder on the alternating side.

In some cases the number of the combustion-cylinders of the motor may be increased. For example, the motor may have three double-acting explosion-cylinders, in which case the three cranks of the motor crank-

shaft require to be set at an angle of one hundred and twenty degrees from each other, and the ratio of the gear-wheels by which motion is transmitted to the pump crank-shaft is to be three to one when a double-acting feed-pump is employed or as six to one when a single-acting feed-pump is employed. 60

Having thus described my invention, I claim as new and desire to secure by Letters 65 Patent—

1. In a two-cycle internal-combustion engine, the combination of a double-acting combustion-cylinder, a power-piston reciprocating in said cylinder, a feed-pump, a piston in 70 said feed-pump, means operatively connecting the power-piston and pump-piston for imparting to the latter a number of strokes which is a multiple of the number made by said power-piston, and means for conducting 75 the explosive charge from said feed-pump alternately to the opposite ends of said combustion-cylinder.

2. In a two-cycle internal-combustion engine, the combination of a double-acting combustion-cylinder, a power-piston reciprocating in said cylinder, a feed-pump, a piston in 80 said feed-pump, means operatively connecting the power-piston and the pump-piston for imparting to the latter double the number of strokes made by the power-piston, and means for conducting the explosive charge from said feed-pump alternately to the opposite ends of said combustion-cylinder. 85

3. In a two-cycle internal-combustion engine, the combination of a plurality of double-acting combustion-cylinders, a power-piston reciprocating in each of the same, a feed-pump, a piston reciprocating in the feed-pump cylinder, means operatively connecting the power-pistons and the pump-piston for imparting to the latter a number of strokes which is a multiple of the number made by said power-pistons, means for supplying an explosive charge alternately to the 90 opposite ends of said feed-pump, and means for conducting the explosive charge alternately from each end of said feed-pump alternately to the opposite ends of said combustion-cylinders. 95

In testimony that I claim the foregoing as my invention I have signed my name in presence of two subscribing witnesses.

105 LUDWIG MERTENS.
